UNITED STATES PATENT OFFICE.

JOHN G. CALLAN, OF BOSTON, MASSACHUSETTS, ASSIGNOR TO GENERAL ELECTRIC COMPANY, A CORPORATION OF NEW YORK.

MEANS FOR PREVENTING SURGING IN CENTRIFUGAL COMPRESSORS.

1,097,298.

Specification of Letters Patent.

Patented May 19, 1914.

Application filed September 28, 1912. Serial No. 722,929.

To all whom it may concern:

Be it known that I, JOHN G. CALLAN, a citizen of the United States, residing at Boston, in the county of Suffolk, State of Massachusetts, have invented certain new and useful Improvements in Means for Preventing Surging in Centrifugal Compressors, of which the following is a specification.

10 This invention relates to centrifugal compressors for elastic fluids, and its object is to improve their construction and operation, whereby the surging, pulsating or puffing effect therein under certain load conditions will be prevented. In a prior application, filed March 16th, 1910, Serial No. 549,748, I have discussed at some length the reasons why this objectionable effect occurs at light loads, and have disclosed one mode of correcting it, namely, by inserting in the intake pipe of the compressor a throttle valve which follows the fluctuations in volume and pressure of the fluid, a damping device being provided to check violent movements 25 of said valve. The present invention deals with the matter further and points out certain fundamental conditions and from these derives certain remedies which I believe are novel and highly valuable at the present state of the art.

In the accompanying drawings, Figure 1 is a sectional elevation of a portion of a centrifugal air compressor showing a regulator embodying my invention; Fig. 2 is a cross-section on the line 2—2, Fig. 1; Figs. 3 to 8 are diagrams showing characteristic curves of a compressor operating under different conditions.

Apparatus for centrifugal compression of 40 fluids employs two principles for generating pressure. The first, centrifugal force; the second, conversion of velocity head into pressure head in suitable inverted-nozzles.

At constant speed the purely centrifugal 45 contribution to the compression remains substantially constant regardless of the amount of fluid (for example air) delivered by the compressor. This is not true of that portion of the final-pressure contributed by 50 the inverted-nozzle action of the "discharge

vanes." These are designed to function best at a certain volumetric output and their efficiency falls off somewhat with any departure from this, and particularly with reduced flow. At constant speed, which ought 55 to generate constant pressure, this falling off of "discharge vane" efficiency exhibits itself by a drop of pressure when the volumetric output is reduced below a certain point. This drop may be gradual or it may 60 nearly all occur at once (break-down point) or it may assume characteristics between these extremes.

Fig. 3 shows a curve with a well marked "break-down point"; Fig. 4 one with this sharp "break-down point" eliminated and the pressure reduction at partial load distributed; Fig. 5 shows what happens to the "break-down point" when the compressor speed is progressively reduced, thus reducing 70 the pressure. In this case any given condition, as for example the "break-down point" or for another example the portion of the curve which should be selected as representing normal load conditions, will 75 find its locus on a parabola of which the

equation is $\frac{V}{\sqrt{P}} = \text{a constant.}$

By use of various expedients these characteristic curves may be made to assume shapes less simple than those here shown but the diagrams are thoroughly illustrative.

Under many commercial conditions it is necessary to operate the compressor at times 85 on the unstable part of its characteristic. Under such conditions the true remedy for instability lies in throttling at a point near the machine, preferably on the inlet but alternatively on the outlet. The reason for 90 this is that a pressure-volume curve for discharge through a throttled orifice necessarily slopes downward as shown by the curve below the axis of V in Fig. 6, and a compressor characteristic plotted upward from this 95 curve as a base line will partake of this downward slope as shown in Fig. 6. That figure shows the result of throttling through a constant orifice; it will be seen that the steadyng action is extremely small at the 100

early stages and becomes progressively greater as the flow increases, the action being approximately proportional to the square of the volume passing. The characteristic is seen to be so modified that the unstable portion becomes shorter than in Fig. 4 and the stable portion correspondingly moves back farther into the region of partial load. On the other hand the drop in pressure and consequent loss in the stable portion is highly objectionable.

As we shall see later, a simple throttled opening is not the best steadyng device, but a study of it leads to appreciation of fundamental conditions. Therefore, we may continue it a little further. To determine the amount of throttling required for a given steadyng effect we should appreciate that if there is just enough throttling to tip the actual working curve from an upward slope to a downward one at a point where the machine is to run, this will change its operation from unstable to stable conditions at that point. The amount of throttling required to do this obviously depends upon two things:—first, inclination or tangent of the inherent or generated characteristic at the point in question, and second, the amount of flow at the point in question, since throttling is a function of volumetric flow. From these data we can determine an opening which will steady the flow and eliminate surging or pulsation at any one given point. It will be at once apparent, however, that the size of opening right for one point is probably too small for all points of larger flow and probably too large for points of smaller flow. The only exception to this would be in the case of a characteristic with marked "break-down point" at which point exceptionally vigorous throttling would be called for and hence requires in many cases an opening actually smaller than that required at points of lesser flow.

It is evident that any throttling whatever produces inefficiency, and hence with the ideal automatic throttle we must apply at any point only just so much throttling as is necessary to insure stability, and where none is necessary must apply none. It has been thought that a check valve or relief valve floating on the incoming or emerging air stream and applying thereto an amount of throttling determined by the weight would effect the necessary steadyng, and in point of fact with commercial degrees of valve friction and inertia some steadyng action is actually thus brought about. As indicated in Fig. 7, however, the action is exceedingly crude, imperfect and ineffectual, since it merely changes the position of the axis of V, or speaking in physical conception, merely imposes a constant pressure drop on the air while in point of fact the essence of the

steadyng action is a pressure drop which is variable in a direction such that increased volume produces increased drop and hence decreased net delivered pressure so far as the steadyng agent is concerned. Therefore, a simple weighted check valve or relief valve floating on the inlet or outlet air stream does not fulfil the conditions of a suitable and economical steadyng device.

Fig. 8 exemplifies what is really wanted. Here the full line gives the generated characteristic of the compressor as measured at the outlet. An ideal throttling action may be assumed which at any given volume superposes upon this characteristic a downwardly sloping (throttled) curve exactly neutralizing at that point the upward slope and leaving the net characteristic perfectly horizontal. Obviously we may over-neutralize to produce extreme stability or under-neutralize to allow for line drop as in an over compounded electric generator. For simplicity, we will consider exact neutralization alone. To realize exactly or approximately the required conditions necessitates two things. First, an arrangement or structure such that at any given flow the automatic throttle will be closed down to an orifice giving the required horizontal characteristic; this for any one point may be accomplished by the weighted check valve or equivalent. Second, a device which will hold this orifice at approximately this value through the period of one cycle of variation under the existing conditions of line resistance and capacity; this can be accomplished for any one periodicity by a dash-pot set to permit valve motion at not more than a certain rate.

With the combination thus formed and the exact proportioning and adjustment thus defined, we have, for any given mean volumetric delivery, a condition of throttling such that any momentary volumetric increase causes at the throttle exactly as much net pressure drop as it causes net pressure rise at the "discharge vanes" and conversely momentary volumetric decrease causes through decreased throttling an increase of net discharge pressure exactly compensating for the decrease of that pressure due to impaired "discharge vane" efficiency. If this condition can be realized at each point of the curve, we shall have established an ideal steadyng device since at no point will the throttling and consequent impairment of efficiency be greater than is absolutely required; and on the other hand the operation will be perfectly steady throughout this range.

In carrying out this invention we may seek to achieve the results defined either exactly or approximately. They may be exactly achieved as follows:—Suppose a

blower characteristic to have been determined and plotted so that the slope $\frac{dp}{dv}$ is known at any point. A series of computations will then be made determining the orifice which at that point would produce complete steadyng action (or any degree of excess or deficiency that may have been determined upon). Next, for that point a computation will be made showing what weight will be required on a suitable valve such as that shown in the illustration in order to maintain the valve opening at the computed orifice when the volume proper to the point in question is passing. A series of such computations will be made for as many points as are required along the curve. From these a cam (or equivalent mechanism such as a wrist plate linkage) will be laid out such that when the valve is opened to a given orifice the weight applied to it will be that shown by the computation in every case. Thus when a given volume is passing, the valve will assume a position such that the throttled orifice which it fixes is exactly that required for the steadyng action necessary at that point. It then is only necessary to maintain this valve in position by a dash-pot stiff enough so that it will not depart by more than a permissible amount from the theoretical orifice during the period which would be occupied by one cycle of rise and fall of pressure as described in my previous patent application. Under these conditions disturbances in the blast line or elsewhere cannot start the cyclic surging which would otherwise take place. Fig. 1 illustrates the application of these principles in practical form. The intake 1 of the air compressor 2 is provided with a throttle valve 3 mounted on a stem 4 which has at its lower end a dash-pot 5. The valve is a disk located in an inverted frusto-conical section 6 of the intake, so that as it rises and falls it enlarges and diminishes the annular opening between its periphery and the wall of the section 6. The stem 4 passes up through the top of the elbow 7 in the intake pipe, and carries a cam 8, whose back 9 is parallel with the path of movement of the stem, and bears against anti-friction guide rollers 10 mounted on a standard 11. A lever having two arms 12, 13 at right angles is pivoted to the upper end of the standard. The vertical arm 12 carries a roller 14 bearing on the cam. A weight 15 is adjustable along the horizontal arm 13. With an increase in the volume of air passing through the intake, the valve rises and the cam tilts the lever, throwing the arm 13 upward and thereby shortening the effective distance of the weight 15 from the pivot, and lessening the pressure of the roller 14 against the cam,

so that the valve is more sensitive to slight changes in volume when working in the upper part of the section 6. The cam shown happens to have an ogee curve, but the exact curve is determined by the calculation hereinbefore mentioned.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. In a centrifugal compressor, means for producing stability of operation which comprises a conduit through which the fluid handled by the compressor flows, a valve movably mounted in the conduit, a weight that tends to oppose the movement of the valve in one direction, a device connected to the valve to move therewith, said device acting to vary the effect of the weight on the valve, and means for damping the movement of the valve.

2. In a centrifugal compressor, means for producing stability of operation which comprises a conduit through which the fluid handled by the compressor flows, a valve movably mounted in the conduit that has a tendency to close and is opened by the action of the fluid, a weight that opposes the opening of the valve, a cam connected to the valve to move therewith, said cam acting to vary the effect of the weight on the valve, and a dash-pot for damping the movement of the valve.

3. In a centrifugal compressor, means for insuring stability of operation which comprises a conduit through which the fluid handled by the compressor flows, a valve arranged in the conduit that has a tendency to close and is opened by the action of the flowing fluid, a stem for the valve, a movable weight that opposes the opening of the valve, a cam carried by the stem which acts to vary the effect of the weight on the valve, and a dash-pot for damping the movement of the valve that has one of its members connected to the valve stem.

4. In a centrifugal compressor, means for preventing surging which comprises an intake pipe having an inverted frusto-conical section, a throttle valve movable in said section, a weighted lever resisting the opening movement of said valve, and a cam on the stem of said valve adapted to actuate said lever and lessen the retarding effect of said weight as the throttle opens.

5. In a centrifugal compressor, means for preventing surging, which comprises an in-

take pipe having an inverted frusto-conical section, a throttle valve movable in said section and consisting of a disk mounted on a stem and floating on the incoming stream of air, an elbow lever having a vertical arm and a weighted horizontal arm, and a cam on the valve stem engaging with the vertical arm of said lever and acting to lift the weighted arm as the throttle opens, said cam being

determined from the characteristic curve of 10 said compressor.

In witness whereof, I have hereunto set my hand September, 1912.

JOHN G. CALLAN.
